CONDIMENT SHAKER

William McArthur, East Orange, N. J.

Application May 2, 1938, Serial No. 205,469

1 Claim. (Cl. 65—45)

This invention relates to improved containers for condiments, such as salt or pepper or other materials, and is especially adapted for use in connection with a plurality of condiments or materials which may be selectively dispensed from the container, although the invention may have many other applications.

The main object of the invention is to provide a device of the character described which shall be simple in construction and efficient in operation.

It is a further object of the invention to provide a shaker for a plurality of separated condiments or other materials which permits the materials to be replenished without danger of mixing one with another.

A further object of the invention is to provide an improved closure cap.

A further object of the invention is to provide an improved relationship of compartments for containing the different materials to be dispensed and the relation of such compartments to the closure cap.

A further and ancillary object of the invention is to provide a container for one material and a receptacle for another material, the receptacle depending from the closure cap.

A further object of the invention is to provide a container having a closure cap with a receptacle depending from the closure cap and means associated with the closure cap for controlling the dispensing of the material from the receptacle and the container.

Where a movable member is movably mounted in relation to the closure cap of a condiment shaker or the like, such movable member controlling openings in the closure to shut off or permit the dispensing of material through such openings, and where such member is arranged inside the closure, there is danger of the controlling member being gripped between the top of the closure and the edge of the container so as to prevent ready movement of the controlling member if the closure is screwed too tight upon the container.

It is a further object of the invention to avoid this disadvantage by placing the movable dispensing control member between the inner and outer members of the closure which are spaced apart and secured together so that ready movement of the controlling member is permitted at all times regardless of how tightly the closure is screwed upon the container.

Other and ancillary objects of the invention will appear hereinafter.

In the accompanying drawing which illustrates the invention:

Fig. 1 is a top plan view of a device embodying the invention adapted for use as a salt and pepper shaker with the control in position where certain of the material exits are closed and others are open.

Fig. 2 is a sectional view of the device on the line 2—2 of Fig. 1.

Fig. 3 is a plan view of the device, similar to Fig. 1 but with the exit control in the opposite limit of its position whereby the open exits of Fig. 1 are closed and the closed exits are opened; and

Fig. 4 is a side elevation of the upper portion of the shaker, the bottom part being broken away.

Referring to the drawing, the device comprises a container 1 of glass, porcelain or other suitable material, having a screw-threaded neck 2 upon which is screwed a sheet metal closure comprising the shell portion 3 having a top wall 4 and a marginal skirt 5 depending therefrom. Within the shell 3 is a cap portion comprising a top wall 6 and a depending marginal skirt 7 in which are formed the screw threads 8 for cooperation with the threads 9 on the container. Centrally depending from the top wall of the cap portion of the closure is a tubular receptacle 10 having its lower end closed by the removable screw plug 11 and at its upper end being connected with the top wall of the cap portion about the margin of the opening 12 in the center of the cap portion. This connection may be formed by soldering or in any suitable way.

Lying with an easy fit between the top walls 6 and 4 of the shell and cap portions of the closure is a control plate 13 rotatable about a central boss 14 upon the plate which enters the central recess 15 in the top wall 4 of the closure shell.

The top wall 6 of the cap portion of the closure is provided with a series of holes 16 communicating with the interior of the container 1 outside the receptacle 10. Directly opposite or registering with the holes 16 are the outer series of holes 17 in the top wall of the closure shell. In the plate 13 is an outer series of holes 18 adapted to be moved into and out of registry with the holes 16 and 17 as the plate is rotated about its center.

Also the plate 13 has an inner series of holes 19 opening to the interior of the receptacle 10, 50 and being movable into and out of registration with an inner series of holes 20 in the top wall 4 of the closure shell, as the plate 13 is turned about its center.

To afford means for moving the plate 13 about 55

its center the plate has a finger piece 21 extending through a slot 22 in the shell portion of the closure, the movement of the cap in either direction being limited by the finger piece coming against the ends of the slot 22 and the holes 16 and 17 are so arranged with relation to the holes 18 in the plate that when the finger piece is at one end of its travel (see Fig. 1), the holes 16, 17 and 18 will afford openings from the interior to the exterior of the cap, but such openings will be closed by the plate 13 when the finger piece 21 is moved to the other end of the slot (see Fig. 3). Also the holes 19 in the plate are in such relation to the holes 20 in the closure shell that when the finger piece is in the position as shown in Fig. 1 the openings 20 will be closed by the plate 13, and when the finger piece is in the position as shown in Fig. 3, openings will be afforded from the interior of the receptacle 10 to the exterior of the cap through the holes 19 and 20.

It will now appear that when the plate 13 is in one extreme position as when the finger piece 21 is against one end of the slot 22 as shown in Fig. 1, communication with the interior of the receptacle 10 with the exterior of the closure will be closed by the plate 13, while communication through the holes from the interior of the container 1 to the exterior of the closure through the holes will be open. When, however, the plate 13 is rotated so that the finger piece 21 is against the opposite end of the slot 22, as shown in Fig. 3, the communication from the interior of the container with the exterior of the closure will be cut off, while communication from the interior of the receptacle 10 with the exterior of the closure will be open. In the position of the plate where the finger piece 21 is intermediate between the ends of the slot 22, the plate 13 will close all the openings through the closure so that communication with the exterior from both the interior of the container 1 and the receptacle 10 will be cut off.

The cap and shell portions of the closure are secured together against both relative, longitudinal and rotational movement by curling the lower edge of the skirt 5 of the shell portion tightly about the lower edge of the skirt of the cap portion, so that the screw-threaded cap portion will be turned by force applied to the outer shell portion in order to screw the closure on to and off the container and also the cap and shell portions of the closure are held properly longitudinally spaced so as not to bind upon and prevent the ready rotation of the plate 13 in the operations as described.

It will be seen that, the device being used as a pepper and salt shaker, the closure and recep-

tacle can be removed from the container and pepper placed in the receptacle apart from the container and salt placed in the container apart from the receptacle so that there is no danger of mixing the salt and pepper in replenishing supplies of the receptacle and container such as is the case where a combined pepper and salt shaker is formed by compartments formed in the container, so that they are permanently located in close relation to each other and there is consequent danger of spilling the pepper into the salt compartment and vice versa.

It will further be observed that a simple and efficient device is provided whereby, by the simple operation of pushing the finger piece into proper position, either salt or pepper may be obtained independently of the other, or the device may be closed against the dispensing of either.

While the invention has been illustrated in what is considered its best application it may have other embodiments without departing from its spirit and is not therefore limited to the structures shown in the drawing.

What I claim is:

The combination with a container, of a closure therefore comprising an outer shell having a substantially flat top wall and a marginal depending skirt, a cap member within said shell and having a substantially flat top wall and a marginal depending skirt, said cap and shell portions being secured together against longitudinal and rotational movement by the curling of the marginal edge of the skirt of one of said members tightly about the skirt of the other of said members, said cap member having a screw thread for operatively engaging with the said container in removable relation, said cap member having a receptacle depending therefrom and entering within said container with a space between it and the container, said cap and shell having two sets of registering dispensing openings, one of said sets being centrally arranged and adapted to permit dispensing from the said receptacle and the other of said sets of openings being arranged outside of said central set and adapted to permit dispensing from said container, a substantially flat plate between the said top walls and rotatable with relation thereto, said plate having two sets of openings corresponding to the said central and outer sets of openings in said top walls, and adapted to control dispensing through said inner sets and outer sets respectively by rotation of said plate, said plate having an operating finger piece and said shell member having a slot through which said finger piece extends to the exterior of the closure.

WILLIAM McARTHUR.
